William F. Mullahy, INVENTOR

BY W. F. MULLAHY

ATTORNEY

UNITED STATES PATENT OFFICE.

WILLIAM F. MULLAHY, OF FORT WAYNE, INDIANA.

WAY-BILL.

SPECIFICATION forming part of Letters Patent No. 738,832, dated September 15, 1903.

Application filed February 9, 1903. Serial No. 142,521. (No model.)

To all whom it may concern:

Be it known that I, WILLIAM F. MULLAHY, a citizen of the United States, residing at Fort Wayne, in the county of Allen and State of Indiana, have invented certain new and useful Improvements in Way-Bills; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to improvements in way-bills for use in handling freight-cars; and the object thereof is to afford a convenient record which will facilitate in directing the return of said cars to the point where received and also to provide means in connection with the foregoing from which to determine the number of days said cars are located on the receiving-railway.

I accomplish my object by the construction and arrangement of the way-bill illustrated in the accompanying drawings, in which—

Figure 1 is a plan showing one side of my way-bill, and Fig. 2 is a plan of the reverse side of same.

Referring now to the letters of reference, A is a card, and B is a series of perforations forming a line down the center of the card, on which the card is suited to be folded and which divides said card into two sections—namely, the card way-bill proper, C, and the coupon D. The said way-bill proper contains printed matter and spaces thereon for recording the initial letters of the car to be handled, its number, shipping directions, and matter usually recorded upon way-bills in common use.

This invention lies particularly in the attached coupon D, upon which is to be recorded the initial letters and number of the car as recorded upon the way-bill proper. A series of spaces E are arranged upon said coupon and are headed by the words "This car routes home." The spaces E are intended to receive the entry of matter showing the name of the place where the car was received and the initial letters of the railway company which delivered the car to the railway company which is to handle said car and by which

latter company this way-bill is to be used. (For the sake of convenience of description the company handling the car will be hereinafter referred to by the fictitious name "Blue River Railway.") The way-bill proper, C, and the coupon D bear the name of the "Blue River Railway," and said coupon bears also the title "Home-route coupon," as shown at F, and printed directions, as shown at G, as follows: "This coupon must accompany car to destination and when made empty car must be handled in accordance with information shown hereon. Should car be reloaded, agent will show above information on card made at his station. When car leaves the line, agent at junction-point will detach coupon and hold it pending the probable return of car." Upon the reverse side of the coupon D, at the top thereof, as shown at H, is printed the following statement: "The following information is for 'per diem' purposes. Care should be taken that the 30-day limit is not overrun." A series of spaces J are arranged upon said coupon beneath said statement to receive the entry of the initial letters of the car being handled and the date when the same was received upon the tracks of the Blue River Railway.

It has now in certain districts become a custom in railway practice for a first railway to pay a second railway for the use of a car of the second railway for the time said car is on the rails of the first railway, the charge being computed at the per diem rate of a certain nominal sum, and a substantial increased sum per diem for the time in excess of a certain number of consecutive days when held by the first railway. It therefore becomes an advantage to the first railway to handle the car of the second railway with despatch, and vice versa. It is also a practice for a first railway to return a car of a second railway to the railway from which said car was received by the first railway and at the junction-point thereon where the said car was received. A practice now in use to direct the handling of a car under above circumstances is to attach to said car a card upon which is entered the name of the junction-point where the same is received. This method is imperfect, for the reason that the entry on said card often becomes indistinct from exposure to

weather, and it frequently occurs that such cards are unofficially removed from cars, thus destroying the function of the entry.

In using my coupon way-bill the way-bill proper and the coupon thereon are filled out as hereinbefore described, and the coupon remains attached to the way-bill proper until the car reaches its destination. The coupon and way-bill proper are held by the official in charge of the car and is delivered by him to the official receiving the car. Example: The Blue River Railway receives at Chicago, its terminal, an L. & N. car loaded and to be transported, and said car was received from the C. & N. W. Ry. at its junction-point at Chicago with the Blue River Railway. My way-bill would be made out by entering upon the way-bill proper the initial letters of the car, its number, name of place of destination, and such other data as is usually placed upon way-bills in common use, and then entering upon the coupon the same letters and number of the car as entered upon the way-bill proper and also in the space E the name of the junction-point and initial letters of the railway from which said car is received, which in the drawings is shown to be "Chicago, C. & N. W. Ry." Upon the reverse side of the coupon D in the spaces therefor provided is entered the initial letters of the railway from which the car was received and the date when received. The way-bill, including the coupon, is then delivered by the official in charge of the car to the agent or other official at the destination or point of delivery. The

coupon is then detached pending the return of the car. If the car is returned empty, the coupon is delivered by the official in charge of the returning car to the agent at the junction-point where first received, who returns the car to the railway from which the car was first received. The said coupon therefore serves in directing the return of the car and also affords data from which can be easily computed the amount of per diem charges. 45

Having described my invention, what I claim as new, and desire to secure by Letters Patent, is—

A way-bill for use in handling railway-cars, comprising a way-bill proper having a detachable coupon in connection therewith, the said coupon having appropriately-designated spaces for the entry of the initial letters and number of the car to be handled; spaces E, designated "This car routes home" or words 55 of like effect, for the entry of the name of the junction-point where, and the initial letters of the railway from which said car is received; and said coupon also containing appropriately-designated spaces J for the entry of the 60 initial letters of the railway from which the car is received and the date thereof, for the purpose specified.

In testimony whereof I affix my signature in presence of two witnesses.

WILLIAM F. MULLAHY.
